UNITED STATES PATENT OFFICE.

PORTR CHAMPLIN, OF POWERS LAKE, NORTH DAKOTA.

WRENCH.

1,239,883.

Specification of Letters Patent. Patented Sept. 11, 1917.

Application filed May 16, 1917. Serial No. 169,103.

To all whom it may concern:

Be it known that I, PORTER CHAMPLIN, a citizen of the United States, residing at Powers Lake, in the county of Burke, State 5 of North Dakota, have invented a new and useful Wrench; and I do hereby declare the following to be a full, clear, and exact description of the invention, such as will enable others skilled in the art to which it 10 appertains to make and use the same.

This invention relates to an improved wrench, adapted for turning nuts and the like.

One of the objects of the invention is the 15 provision of a wrench having a jaw disposed substantially on a forty-five degree angle, in combination with a shank provided with a guide, said shank being detachably connected to the handle of the wrench, 20 whereby a second jaw of the wrench may be mounted in or removed from the guide of said shank.

A further object of the invention is the 25 provision of guide means at right angles to the stationary jaw, which is on a forty-five degree angle, whereby the removable jaw may be guided toward and from the stationary jaw.

A further object of the invention is the 30 provision of means in the guide of the shank for adjusting the removable jaw.

A further object of the invention is the 35 provision of an improved wrench having its jaws disposed whereby nuts or the like may be more conveniently and efficiently handled in obscure places.

In practical fields, the details of construction may necessitate alterations falling 40 within the scope of what is claimed.

The invention comprises further features and combination of parts, as hereinafter set forth, shown in the drawings and claimed.

In the drawings:

Figure 1 is a view in side elevation of the 45 improved wrench, constructed in accordance with the invention.

Fig. 2 is a view in side elevation showing the jaws of the wrench closed.

Fig. 3 is a longitudinal sectional view.

Fig. 4 is an edge view of the wrench.

Fig. 5 is a sectional view on line 5—5 of Fig. 2, through the coöperating jaws.

Referring more especially to the drawings, 55 1 designates a handle of the wrench, the opposite sides of which are provided with suitable depressions 2 having serra-

tions 3, whereby the hand of the user may be insured against slipping. One end of the handle is provided with bifurcations 4, and the lateral ears 5 caused to be formed 60 by said bifurcations, are provided with apertures 6, for the reception of the headed pins 7. The wrench is provided with a stationary jaw 8, which is so disposed that its jaw or nut engaging face 9 is disposed substantially on a forty-five degree angle to the handle of the wrench. The jaw 8 is provided with a shank 10, constructed with a bifurcation or guide 11, and the forks 12 of said shank are secured upon the pins 7 65 between said ears 5 of said handle, as shown in Figs. 2 and 3 clearly. Mounted in the guide or bifurcation 11 so that its opposite recesses 13 will receive the adjacent edges of the forks 12, is an adjustable or sliding 70 block or cross head 14. The outer faces of this block or cross head are provided with guide grooves 15 extending at right angles to the recesses 13. A suitable screw 16 is threaded into the sliding block or cross head 75 14, and has its extremity 17 engaging the crotch of the guide 11, while its other reduced end 18 engages the socket 19 of one end of the handle 2. The screw 16 has a knurled enlargement 20, in order to be 80 turned by the thumb, for adjusting the sliding block or cross head in the guide 11. The movable or adjustable jaw 21 is also disposed substantially on a forty-five degree 85 angle to the handle of the wrench, so as to coöperate with the jaw 8. On the end of the shank 10 adjacent the jaw 8, a comparatively thin blade 22 is constructed, and on opposite sides of this blade, where it merges into the jaw 8, are guide openings 90 23. The jaw 21 is provided with a bifurcation 24, and this bifurcation, adjacent its crotch, is of a thickness sufficient to receive the blade 22. The jaw 21 is provided with spaced projecting blades 25, between which the blade 22 extends, while the blades 25 pass through the guide openings 23. The adjacent walls of the bifurcation beyond that portion which receives the blade 22, are provided with guide recesses 26, to receive the opposite ribs 27 of the shank 10. The ribs 27 extend at right angles to the nut engaging face 9, as shown in Figs. 1 and 2 clearly. The adjacent faces of the bifurcation 24, at the extremities of the forks 28 of the jaw 21 are provided with transverse 95 guide grooves 29 (which receive the ribs 30

of the sliding block or cross head) and the adjoining ribs 31, which engage the guide grooves 15 of the outer side faces of said sliding block or cross head. It is to be noted 5 that by turning the screw 16, by manipulating the knurled enlargement 20, the sliding block or cross head will be adjusted in its guide 11 in one direction or the other. When moving the sliding block or cross 10 head toward the outer end of its guide, the jaw 21 will be moved toward the jaw 8, and a reverse movement of the sliding block or cross head will move the jaw 21 in the opposite direction, said jaw 21 all the while 15 being accurately adjusted.

The invention having been set forth, what is claimed as new and useful, is:—

20 In a wrench, a handle, a stationary jaw having its jaw face substantially at a forty-five degree angle to the handle and having guide openings and provided with an adjoining blade, said stationary jaw having a shank provided with a guide and being connected to the handle, a block or cross head slidably

25 mounted in the guide and provided on its outer face with transverse guide grooves, a movable jaw having a bifurcation, the crotch of which receives said blade, the adjacent faces of the bifurcation having 30 grooves, said shank adjacent the stationary jaw having ribs to engage said grooves, said movable jaw having forks caused to be formed by said bifurcations, said forks of the movable jaw having means to engage the transverse guide grooves of said block, 35 and a screw having one end in a bearing of the handle and its other end engaging the crotch of the guide of said shank, and threaded through the block for adjusting the same. 40

In testimony whereof I have signed my name to this specification in the presence of two subscribing witnesses.

PORTER CHAMPLIN.
